UNITED STATES PATENT OFFICE.

DELMAR G. ROOS, OF BRIDGEPORT, CONNECTICUT, ASSIGNOR, BY MESNE ASSIGNMENTS, TO THE LOCOMOBILE COMPANY, OF BRIDGEPORT, CONNECTICUT, A CORPORATION OF DELAWARE.

ENGINE.

Application filed February 5, 1919. Serial No. 275,221.

To all whom it may concern:

Be it known that I, DELMAR G. Roos, a citizen of the United States, and a resident of Bridgeport, in the county of Fairfield and 5 State of Connecticut, have invented an Improvement in Engines, of which the following description, in connection with the accompanying drawings, is a specification, like characters on the drawings representing like 10 parts.

This invention relates to engines of the class in which a cylinder casting and the caps for the main bearings of the crank-shaft are secured to the crank-case by studs.

15 The invention is more particularly concerned with a construction in which a single set of studs take the action and reaction of the cylinder and the bearing caps, while permitting removal of either without disturbing 20 the other, and without removal of the studs. Another feature relates to the relative arrangement of the studs and the oil ducts leading to the main bearings.

My invention will be best understood by 25 reference to the following description, when taken in connection with the accompanying drawings of one specific embodiment there- 30 of, while its scope will be more particularly pointed out in the appended claims.

In the drawings:

Fig. 1 is a side elevation of an engine embodying my invention;

Fig. 2 is a sectional view on line 2—2 of Fig. 1; and

35 Fig. 3 is a sectional view on an enlarged scale on line 3—3 of Fig. 1.

Referring to the drawings, and to the embodiment of my invention which is illustrated therein, I have shown for purposes 40 of exemplification an internal combustion engine comprising a cylinder casting 4 mounted on a crank-case 5, the latter forming a housing for a crank-shaft 6. The latter is mounted in a plurality of main bearings 7 provided with caps 8 which, in the present example, are formed in two parts, as shown in Fig. 3, although this is not at all necessary.

It is well known that in an engine of this 50 class, the operation of the pistons, connecting rods and cranks, produces an action and reaction tending to drive the cylinder casting in an upward direction, and the main-bearing caps in a downward direction. As 55 a means to take this action and reaction, I

have provided for each main-bearing a plurality of tension members, herein a pair of studs 9 connecting the cylinder casting and bearing cap to the crank-case. Preferably, the crank-case is provided with a deep vertical web 10, through which the studs 9 extend. The upper terminal portions of the studs extend through a suitable portion of the cylinder casting, herein a flange 11, and are threaded to receive nuts 12 and lock-nuts 13, while the lower terminal portions of the studs are similarly threaded to receive nuts 14 and lock-nuts 15. Thus it will be understood that the studs transmit the downward thrust of the bearing caps to the cylinder, and on the other hand transmit the upward thrust of the cylinder to the bearing caps, thereby relieving the crank case of these stresses which would otherwise tend to tear it apart.

As a means to permit removal of the cylinder without disturbing or releasing the bearing cap and studs, and on the other hand to permit the removal of the cap without disturbing or releasing the cylinder and studs, I provide the latter with suitable means of attachment to the crank-case. To this end, the studs 9 herein have screw-threaded engagement with the crank-case 5, as at 16. It should here be noted that the cylinder flange 11 is provided with stud-receiving openings 17, which loosely receive the studs 9. When, therefore, the nuts 12 and 13 are removed, the cylinder 4 may be withdrawn in an upward direction without disturbing the cap 8 and studs 9, since the latter are secured to the crank case 5 independently of the attachment of the cylinder 4 thereto. On the other hand, by removing the nuts 14 and 15, the cap 8 may be removed in a downward direction without disturbing the cylinder 4 or studs 9, since the latter are secured to the crank-case 5 independently of the caps. Moreover, the cylinder, as well as the cap, may be removed while still leaving the studs in place. Preferably, the studs are provided with oppositely facing shoulders 18 and 19, abutting respectively against the crank case 5 and cap 8. When, therefore, the nuts 14 and 15 are tightened, the cap 8 is forced against the shoulder 19. On the other hand, when the nuts 12 and 13 are tightened, the thrust is received by the shoulder 18, thereby preventing any possibility of stripping the threads at 16, since

the latter are formed in the crank-case 5 which is usually aluminum, and hence unable to withstand severe stress of this kind without shearing of the screw-threads.

- 5 Thus it is evident that the studs take the action and reaction of the cylinder and main-bearing caps, while still permitting either to be removed without unfastening the other and without disturbing the studs.
- 10 The convenience of this will be readily appreciated.

Where the main bearings receive their supply of oil from ducts extending laterally from one side of the crank case, interference 15 owing to the presence of one of the studs 9 is avoided by providing an annular chamber 20 encircling the stud and communicating with ducts 21 and 22, which are in line with the stud. The duct 22 receives its supply of 20 oil from a usual main supply duct 23 extending lengthwise of the crank-case. Thus the chamber 20 provides a path for the oil about the stud 9, and incidentally provides a reservoir in which a small amount of oil 25 will remain stored, thereby to provide a supply for a limited time in case of failure of the main supply. It should here be noted that the shoulder 18 provides a seal at the bottom of the chamber, while the screw-thread 30 16 provides a seal at the top, thus preventing any possibility of the escape of the oil.

Having thus described one embodiment of my invention, what I claim and desire by 35 Letters Patent to secure is:

1. In an engine, the combination of a cylinder, a crank-case, supporting said cylinder, a crank-shaft, a crank-shaft main bearing comprising a cap, and means to take 40 the action and re-action of said cylinder and cap and to secure each to said crank-case independently of the other, said means comprising two nuts and a tension member onto which said nuts are threaded, said tension 45 member having a shoulder facing one of said nuts and cooperating therewith to secure said cylinder to said crank-case.

2. In an engine, the combination of a cylinder, a crank-case supporting said cylinder, a crank-shaft, a crank-shaft main bearing comprising a cap, and means to take 50 the action and reaction of said cylinder and main bearing, and to secure both to said crank-case, said means including a tension member having an upwardly facing shoulder abutting against said crank-case to prevent lengthwise movement of said member toward 55 said cylinder and provided above said shoulder with a screw-thread threaded into said crank-case to prevent lengthwise movement of said member toward said cap.

3. In an engine, the combination of a cylinder, a crank-case supporting said cylinder, a crank-shaft, a crank-shaft main bearing comprising a cap, and means to take 60

the action and reaction of said cylinder and main bearing, and to secure both to said crank-case, said means including a tension member having oppositely facing shoulders abutting respectively against said crank-case and said cap. 70

4. In an engine, the combination of a cylinder, a crank-case supporting said cylinder, a crank-shaft, a crank-shaft main bearing comprising a cap, and means to 75 take the action and reaction of said cylinder and main bearing, and to secure both to said crank-case, said means including a tension member having oppositely facing shoulders abutting respectively against said crank-case and said cap, a nut threaded into one 80 terminal portion of said member and cooperating with one shoulder to clamp said cylinder and said crank-case therebetween, and a nut threaded onto the other terminal portion and cooperating with the other shoulder to clamp said cap therebetween. 85

5. In an engine, the combination of a cylinder, a crank-case, a crank-shaft, a crank-shaft main bearing comprising a cap, and means to secure said cylinder and said cap to said crank-case, said means including 90 a pair of studs extending through parts of said cylinder, crank-case and cap, said studs having screw-threaded engagement with said crank-case and being provided with enlargements having oppositely facing shoulders abutting respectively against said crank-case and said cap, nuts threaded onto one pair of ends of said studs to secure said cylinder to said crank-case, and nuts threaded onto the other pair of ends of said studs to secure said cap to said crank-case. 95

6. In an engine, the combination of a crank-shaft, a crank-case, a cylinder provided with a flange resting on said crank-case, a crank-shaft main bearing comprising a cap, distinct from and within said crank-case, and means to secure said cylinder and said cap to said crank-case, said means including a pair of studs extending through said flange and through said cap and having independent means of attachment to each and to said crank-case. 100

7. In an engine, the combination of a crank-shaft, a crank-case, a cylinder resting on said crank-case, a crank-shaft main bearing comprising a cap, and means to secure said cylinder and said cap to said crank-case, said means including a stud having screw-threaded engagement with said crank-case and screwed thereinto from the inside thereof, said stud being provided with a shoulder which is brought against the inner side of said crank-case in thus screwing said stud into place. 110

8. In an engine, the combination of a crank-shaft, a crank-case, a cylinder resting on said crank-case, a crank-shaft main bearing comprising a cap, and means to secure 115

said cylinder and said cap to said crank case, said means including a stud having screw-threaded engagement with said crank-case and provided with a shoulder facing toward said cylinder, said crank-case having a portion which is under compression between said shoulder and said cylinder.

9. In an engine, the combination of a cylinder having a lateral projection provided with an opening, a crank-case supporting said cylinder, a crank-shaft, a crank-shaft main bearing comprising a cap, and means to take the action and reaction of said cylinder and cap and to secure both to said crank-case, said means comprising a tension member provided with an enlargement pre-

senting a shoulder seated in an upward direction against said crank-case, a shank extending from said shoulder in an upward direction, threaded into said crank-case and having a terminal portion extending through said opening, said member having a shank extending from said enlargement in a downward direction through said cap, and provided with a threaded terminal portion, and nuts threaded onto said terminal portions, respectively, to secure said cylinder and cap to said crank-case.

In testimony whereof, I have signed my name to this specification.

DELMAR G. ROOS.
